UNITED STATES PATENT OFFICE

EARL C. ALEXANDER, OF GLEN ELLYN, ILLINOIS, ASSIGNOR TO MASSEY CONCRETE PRODUCTS CORPORATION, OF CHICAGO, ILLINOIS, A CORPORATION OF VIRGINIA

CROSSING SLAB

Application filed January 12, 1931. Serial No. 508,199.

This invention relates to concrete slabs, and particularly to crossing slabs adapted for use in constructing a roadway over railroad grade crossings and for other purposes.

5 One of the objects of the invention is to provide an improved concrete slab.

A further object of the invention is to provide an armored reinforced concrete slab which may be economically and expeditiously 10 fabricated with the aid of standard material.

A further object is to provide an improved armoring frame adapted to be located around the edges of a slab and to be directly secured 15 to the concrete.

Other objects and advantages will appear from the following description of the invention taken in conjunction with the accompanying drawings, in which

20 Figure 1 is a plan view of a railroad crossing embodying my invention.

Figure 2 is a longitudinal sectional view taken on the line 2—2 of Fig. 1.

Figure 3 is a transverse sectional view 25 taken on the line 3—3 of Fig. 1.

Figure 4 is a plan view of a single slab on a larger scale.

Fig. 5 is a side elevational view of same.

Fig. 6 is a sectional view of same on the 30 line 6—6 of Fig. 4.

Fig. 7 is a plan view, partly in section, of a modified form of slab.

Fig. 8 is a side elevation thereof; and

Fig. 9 is a sectional view of same on the 35 line 9—9 of Fig. 7.

Referring to Figs. 1 to 3 of the drawings, the rails 10 of the railroad are supported upon ties 11, being secured thereto by spikes 12. In order to build a roadway across the

40 track, I place upon the ties 11, between, and on the outer side of the rails 10, concrete slabs 13. The slabs 13 are preferably of a thickness equal to the height of the rails so that their upper surfaces lie in the same

45 plane. As shown in the drawings, I prefer to employ a single row of slabs along the outer side of each rail, and I prefer to employ two rows of slabs between the rails. It will be understood that I do not intend 50 to be limited to the number of rows of slabs

employed in either position. The number of slabs used in each row depends upon the length of the slabs and the width of the roadway which is to be constructed and may be varied as desired.

The outermost rows of slabs may abut upon the surface layer 14 of the adjacent roadway. Their inner edges are maintained in spaced relation with respect to the rails 10, by means of fillers or blocks 15 which bear upon the inner faces of the slabs 13 and upon the vertical web of the rail 10, the filler being formed to extend inwardly between the head and base flange of the rail. The fillers 15 may suitably be formed of wood, and may be cut 65 away adjacent the rail joints as shown at the right hand side of Fig. 3 to accommodate the outer splice bar.

The inner faces of the slabs 13 between the rails 10 abut upon each other. Their outer faces are maintained in spaced relation to the rails 10 by suitable spacers 16, which may suitably be constituted by sections of old rails, of which the base flange rests upon the outer faces of the slabs and the head abuts upon the vertical web of the rail 10. The spacers 16 may be of any desired length and various lengths may be located end to end in building a crossing. A gap may be left as shown in Figs. 1 and 3 to accommodate the inner 70 splice bar at a rail joint.

Each slab is internally reinforced by longitudinal steel rods 17 and transverse steel rods 18 which need not be connected to each other. Each slab is provided around its edges with an armoring frame 19 which protects the concrete from the severe shocks applied to the corners by the wheels of the vehicles passing over the crossing.

In the form of slab shown in Figs. 1 to 6, the frame 19 is formed from standard channel material 20, preferably having an inward rib or corrugation 21 in the center of the main web. To fabricate the frame two long lengths 22 are cut to provide the sides, and two short lengths 23 are cut to provide the ends of the frame. The transverse edges of the side webs of the sides 22 are placed in abutment with the outer edges of the side webs of the ends 23 adjacent their ends and 85 90 95 100

are welded together top and bottom providing a complete frame having openings 24 at the corners. It will be noted that no material is wasted in this method of assembling the frame, and that the operations involved are extremely simple consisting in cutting the channel to appropriate lengths and welding the side webs together at the corners.

It will be understood that this method of assembly is capable of modifications for which I intend to be broadly protected. Thus instead of locating the side members between the end members, I may locate the end members between the side members, or I may abut 10 one end of a side member against the inner edges of the flanges of one end member and abut the other end member against the inner edges of the flanges of said side member, adjacent its other end, and so forth.

20 The sides 22 are preferably provided with openings 25 and cored openings 26 are provided in the concrete in alignment therewith to receive eye-bolts or other tools for hoisting and handling the slabs.

25 In fabricating the slabs the frame is placed in a suitable surrounding mold or box to close the openings 24, and suitable cores are placed in the openings 25 to produce the openings 26 in the concrete. The reinforcing rods 17 and 18 are inserted within the frame and are supported in desired position by means of wires or other suitable supports. The rods 17 and 18 are not secured to the frame and they may be placed in position easily and expeditiously.

30 The concrete 27 is then poured into the frame enclosing the rods 17 and 18 and filling the channel 20 and the openings 24. When the concrete is set the finished slab 40 is removed from the mold or box, the cores are removed from the openings 26 and the slab is ready for shipment.

35 In the modification shown in Figs. 7 to 9 inclusive, the armoring frame 28 consists of a flat strip of metal 29 which is bent into rectangular form to provide the sides 30 and ends 31. One side 30 carries an integral extension 32 which is bent to engage the free end of the adjacent end 31 to which it may 50 be welded or secured in any other suitable manner. In order to secure the frame 28 to the concrete 27, I preferably stamp out of the metal of the frame 28 a large number of strips 33, which are bent inwardly. The 55 inner end of each strip 33 is slit or bifurcated, and the resulting prongs 34 are bent in opposite directions to give the strips a firm anchorage in the concrete. In this modification reinforcing rods 17 and 18 are preferably employed and the method of completing the 60 construction of the slab may be substantially the same as that described in connection with the modification of the invention first described.

65 Although I have described the invention

in connection with the specific details of preferred embodiments thereof, it must be understood that such details are not intended to be limitative of the invention except insofar as set forth in the accompanying 70 claims.

Having thus described my invention, what I claim as new and desire to secure by Letters Patent is:

1. A concrete slab comprising a frame of 75 uniform channel section extending about the sides of the slab, the side webs of said channel are directed inwardly around the frame, and a concrete filling in the frame.

2. A concrete slab comprising a frame of 80 channel section, the side webs of which are directed inwardly around the frame, reinforcing rods within the frame and unsecured thereto, and a concrete filling in the frame.

3. A crossing slab comprising a frame of 85 channel section of width equal to the height of a rail, the side webs of the frame being directed inwardly around the frame, reinforcing rods within the frame and unsecured thereto, and a concrete filling in the frame. 90

4. A concrete slab comprising a frame composed of lengths of channel section, the side webs of which are directed inwardly of the slab, said frame being assembled by welding the end edges of the side webs of one 95 length to the inner edges of the side webs of another length near an end thereof, leaving an opening adjacent each corner, and concrete within the frame filling the channels and closing said openings. 100

5. A concrete slab comprising a frame composed of lengths of channel section, the side webs of which are directed inwardly of the slab, said frame being assembled by welding the end edges of the side webs of one 105 length to the inner edges of the side webs of another length near an end thereof, leaving an opening adjacent each corner, reinforcing rods within the frame and unsecured thereto, and concrete filling the frame and closing said openings. 110

6. A crossing slab comprising a frame of 115 channel section of width equal to the height of a rail, the side webs of the frame being directed inwardly around the frame, said frame being assembled by welding the end edges of the side webs of one length to the inner edges of the side webs of another length near an end thereof, leaving an opening adjacent each corner, reinforcing rods 120 within the frame and unsecured thereto, and concrete filling the frame and closing said openings.

7. A concrete slab comprising an armoring 125 frame formed of sheet metal, inwardly directed strips formed from the metal of the frame and a concrete filling in which the strips are embedded, thereby anchoring same to the frame.

8. A concrete slab comprising an armoring 130

frame formed of sheet metal, inwardly directed strips stamped from the metal of the frame, a concrete filling in which said strips are embedded, and means on said strips providing secure anchorage thereof in said concrete.

9. A concrete slab comprising an armoring frame formed of sheet metal, inwardly directed strips formed from the metal of the frame, reinforcing rods in the frame and unsecured thereto, and a concrete filling embedding the strips and rods whereby the concrete is secured to the frame and is reinforced.

15 10. A crossing slab comprising an armoring frame formed of sheet metal of width equal to the height of a rail, inwardly directed strips stamped from the metal of the frame, the free ends thereof being bifurcated and 20 bent in opposite directions, reinforcing rods in the frame and unsecured thereto, and a concrete filling within the frame embedding the strip and the rods whereby the concrete is secured to the frame and is reinforced.

25 11. A concrete slab comprising a metal frame of channel section, the side flanges of said channel being directed inwardly around the frame and said frame comprising a pair of end channels and a pair of side channels, 30 each of said channels being formed with end edges extending substantially parallel to the direction of the adjacent channel and the side webs of each channel being secured to the side webs of each successive channel 35 in the frame to eliminate the waste of material in the cutting of said channels, and a filling of concrete in said frame, flush with the upper surfaces of said side flanges and extending into the channels between said 40 side flanges.

In witness whereof, I hereunto subscribe my name this 6th day of January, 1931.

EARL C. ALEXANDER.
